UNITED STATES PATENT OFFICE.

LEONARD HUGH BONNARD, OF LONDON, ENGLAND.

RETORT AND FURNACE.

Application filed December 1, 1922. Serial No. 604,418.

To all whom it may concern:

Be it known that I, LEONARD HUGH BONNARD, a subject of the King of England, residing at London, in England, have invented certain new and useful Improvements in Retorts and Furnaces, of which the following is a specification.

This invention consists of improvements in or relating to retorts and furnaces.

10 The primary object is to provide a muffle furnace or retort in which carbonaceous material of vegetable origin (such as sawdust) may be subjected to destructive distillation or to carbonization, but the invention is applicable to a variety of different types of retorts and furnaces in which pulverulent material, or even a sludge, is subjected to heat treatment.

Materials such as are above referred to 20 include vegetable materials, crushed ores, and so forth, and are hereinafter referred to as mobile material. Under the term "furnace" as used in the following specification and claims there are to be understood to be 25 included retorts, and generally any form of the apparatus, whether it be heated externally or by the passage of hot gases through the interior or otherwise.

Various types of furnaces are known in 30 which there is a vertical series of horizontal trays to support the mobile material, and in which rakes or blades (which may radiate from a central rotatable shaft) serve to keep the mobile material turned over or agitated 35 and also serve to transfer the material from tray to tray. One well-known example of such apparatus is the "Wedge" mechanical furnace. I make no claim to these known arrangements.

40 Where the mobile material is to be subjected to heat treatment on a series of trays, it is desirable in the first place that the mobile material fed to the apparatus should be distributed in substantially uniform layers (which may be thin layers) on the surfaces of the trays. It is also desirable that the material be turned over from time to time to expose fresh portions to the surfaces of the trays, and that the material 45 should be bodily moved over the surfaces of the trays from the point of delivery to the tray to the point of transfer to the next tray. The object of this invention is to 50 carry out these operations in a simple and 55 effective manner.

According to this invention in a mechani-

cal retort or furnace there is provided the combination of a series of superposed horizontal trays having transfer openings for passages of mobile material from tray to tray, blades overlying the trays, means for moving the blades over the surfaces of the trays and means for raising and lowering the blades in relation to the trays so that they act alternately to spread the material 60 over the tray surfaces and to transfer it toward and through the transfer openings.

More specifically this invention comprises in a mechanical furnace the combination of 70 a series of superposed horizontal trays having transfer openings for passage of mobile material from tray to tray, a vertical rotatable shaft extending through the trays, blades carried upon the shaft so as to overlie the trays and means for raising and lowering the shaft with its blades in relation to the trays so that the blades alternately spread the material over the tray surfaces and transfer it toward and through the 75 transfer openings.

In the accompanying drawings which illustrate diagrammatically one form of muffle retort embodying this invention and specially suitable for the carbonization of sawdust and for the heat treatment of decolorizing carbons.

Figure 1 is a central vertical section showing the general arrangement of the apparatus;

Figure 2 is a vertical section partly in elevation illustrating the retort proper; 90 Figures 3, 4, 5, and 6 are diagrams illustrating the positions of the discharge holes in the hopper, the top feed plate, the uppermost tray, and the second tray, respectively; 95

Figure 7 is a horizontal section on the line 7—7 of Figure 2.

Referring first to Figure 1, an outer annular brickwork setting 1 is separated from the vertical cylindrical retort 2 by an annular space 3 into which project tangentially a series of gas or liquid-fuel burners 4, disposed near the bottom of the apparatus. The retort 2 discharges through an outlet 5 into a conveyor chamber 6 provided 100 with a gas outlet 7 from which the products of distillation are led to a condenser and to a conduit for the residual gas which may be used for heating purposes. The conveyor chamber 6 contains a horizontal worm conveyor 8, and the chamber 6 is surrounded 105 for a portion of its length by a water tank 110

9. The treated and cooled material is discharged from the chamber 6 through a vertical outlet 10 and an expansion pipe 11 into a receiver 12 which is normally kept sealed 5 against the access of air and can be readily replaced when filled.

The retort proper comprises an outer cylindrical casing 13 around which the heating medium or flame passes. Within this casing 10 is a vertical series of fixed horizontal trays 14 which derive their heat from the casing and transfer the heat to the sawdust which is distributed over the surfaces of the trays. Transfer openings in the form of 15 slots 15 are provided in the trays for the transfer of the sawdust gradually through the apparatus. The slots may be sector-shaped and the slot in each tray may be so arranged in relation to the slot in the tray 20 next above it that the sawdust has to travel almost completely round the tray before its discharge therefrom. A central vertical rotatable shaft 16 passes through the axes of the trays 14 and carries radial blades 17; 25 as shown in Figure 7 there may be five radial blades for each tray. The shaft 16 is free to move slightly in a vertical direction, and may be supported on a transverse bar 18 carrying at its ends two rollers 19 engaging 30 an upwardly-facing co-axial fixed cam surface 20 which determines the periodic vertical movement of the shaft. It will be obvious that various alternative methods 35 may be employed for imparting the vertical movement to the shaft. In the form shown a spur wheel 21 with long teeth is secured to the shaft and engages with a corresponding spur wheel 22 secured to a counter-shaft 23, having a driving pulley 24. To 40 prevent undue load on the cam, the shaft and the attached members may be counter-balanced to a considerable extent, say by a pivoted lever 25 and an adjustable weight 26. The object of the vertical movement 45 of the shaft is to enable the radial blades 17 to be moved when required into contact with the surfaces of the trays, and to be raised when required to a certain small distance from the trays, so as to spread the sawdust 50 in thin layers over the surfaces of the trays. For example, in the case where the cam or the like allows the blades to be in contact with the trays during a rotation of about 36°, and then raises the blades during a rotation of about 144°, the operation is as follows:—

From a suitable feed hopper 27, having an outlet 28 through the cover of the retort, the sawdust falls on to a feed plate 29, having a slot 30 therein. A radial feed-arm 31 secured to the shaft 16 sweeps a certain regulated quantity of sawdust away from under the hopper outlet 28 through the slot 30 on to the topmost of the trays 14.

65 Figures 3, 4, 5 and 6 indicate the relative

positions of the slots 28, 30 and 15, the radial arms or blades being assumed to rotate clockwise when looking down upon them, so that as soon as the sawdust is swept away from the hopper hole 28 it passes almost at once through the slot 30 in the feed plate, but on each of the trays 14 the sawdust has to be passed almost completely round the tray before it is discharged therefrom. During a rotation of the shaft 70 through 144° the heap on the topmost tray is spread out on the surface of the tray. The blades 17 are then lowered into contact with the tray, and these blades, in moving through an angle of 36° in contact with the 75 tray, effect a certain forward movement of the sawdust over the surface, and also turn over the material to a certain extent. The blades 17 are then again raised and effect the spreading during a further 144° rotation. By this alternate spreading and shifting the material is gradually transferred through the furnace and it will be noted that in using five radial blades which are in contact with the tray twice for 36° in each 80 revolution, the whole surface of each tray is swept over by the blades at each revolution.

Roughly speaking, the finer the material treated the thinner should be the layers when spread out. Working with sawdust 85 of 32 mesh to the linear inch, quarter-inch layers can conveniently be used.

Apparatus for feeding the mobile material to the retort or furnace may take various forms, it being only necessary that a 100 periodic discharge of the mobile material on to the topmost tray should take place at a suitable place and at appropriate times.

The blades may take a variety of forms, and may, if desired, be specially cooled, e. g. 105 water-cooled.

The method of heating the mobile material may be modified in various ways, for example, in the case of the roasting of ores, the hot gases may actually pass up through 110 the retort itself and be brought in contact with the mobile material.

It is desirable, on the one hand, not to leave portions of the tray surfaces bare or unoccupied for any considerable period, 115 and, on the other hand, not to leave portions of the tray surfaces which are never swept over by the blades whilst in contact therewith.

The number of radial blades employed 120 and the timing of their vertical movements can be readily selected to effect both these objects.

To this end it is useful to point out that where the blades are lowered into contact 125 with the tray at uniform intervals more than once in a revolution, the period of contact necessary depends both on the number of blades and on the number of times of contact, and is inversely as the least common 130

multiple of these two factors. Thus for a given period of contact the maximum sweeping of the surface with the minimum number of blades is obtained if the number of the blades and the number of times of contact are incommensurable (prime to one another). For example, where the blades are lowered twice in a revolution the blades should be of an odd number.

10 What I claim as my invention and desire to secure by Letters Patent is:

1. In a mechanical furnace the combination of a series of superposed horizontal trays having transfer openings for passage 15 of mobile material from tray to tray, blades overlying the trays, means for moving the blades over the surfaces of the trays to feed forward the material and means for raising and lowering the blades in relation to the 20 trays so that they act alternately while moving in the direction to feed forward the material to spread the latter over the tray surfaces and to transfer it toward and through the transfer openings.

25 2. In a mechanical furnace the combination of a series of superposed horizontal trays having transfer openings for passage of mobile material from tray to tray, a vertical rotatable shaft extending through 30 the trays, blades carried upon the shaft so as to overlie the trays and means for raising and lowering the shaft with its blades in relation to the trays so that the blades while moving in the direction to feed forward the 35 material alternately spread the latter over the tray surfaces and transfer it toward and through the transfer openings.

3. In a mechanical furnace the combination of a series of superposed horizontal 40 trays having transfer openings for passage of mobile material from tray to tray, a vertical rotatable shaft extending through the trays, blades carried upon the shaft so as to overlie the trays and a cam and roller device mounted as to one element upon the shaft and as to the other element on a fixed part of the furnace so as, during rotation of the shaft in the direction to feed forward the material, alternately to raise the shaft 45 with the blades in relation to the trays to spread the material and to lower it so that the blades contact with the tray surfaces and transfer the material toward and through the transfer openings.

50 4. In a mechanical furnace the combination of a series of superposed horizontal trays having transfer openings for passage of mobile material from tray to tray, a vertical rotatable shaft extending through 55 the trays, blades carried upon the shaft so as to overlie the trays, a roller mounted upon the shaft, and a fixed cam co-axial with the shaft below the roller so as, during rotation of the shaft in the direction to feed forward 60 the material, alternately to raise the shaft 65

with the blades, in relation to the trays to spread the material and to lower it so that the blades contact with the tray surfaces and transfer the material toward and through the transfer openings.

5. In a mechanical furnace the combination of a series of superposed horizontal trays having transfer openings for passage of mobile material from tray to tray, a vertical rotatable shaft extending through the 70 trays, blades carried upon the shaft so as to overlie the trays, two rollers carried upon the shaft on opposed sides thereof and a fixed cam co-axial with the shaft below the rollers so as, during rotation of the shaft in 75 the direction to feed forward the material, alternately to raise the shaft with the blades in relation to the trays to spread the material and to lower it so that the blades contact with the tray surfaces and transfer the material toward and through the transfer openings.

6. In a mechanical furnace the combination of a series of superposed horizontal trays having transfer openings for passage of mobile material from tray to tray, a vertical rotatable shaft extending through the trays, means for raising and lowering the shaft in relation to the trays more than once in each revolution and blades carried upon the shaft so as to be lowered into contact with the trays when the shaft is lowered, the number of blades for each tray being incommensurable with the number of times of contact of the blades with 95 the trays per revolution.

7. In a mechanical furnace the combination of a furnace casing having a delivery opening to the interior at the top, a feed plate within the casing below the delivery opening, a series of superposed horizontal trays within the casing below the feed plate having transfer openings for passage of material from tray to tray, a central vertical rotatable shaft extending through the 105 trays to the outside of the casing, blades carried upon the shaft so as to overlie the trays, a feed arm rotated with the shaft so as to pass between the delivery opening and the feed plate, and to sweep a portion of material from below the delivery opening and off the feed plate on to the first tray, and means for raising and lowering the shaft with its blades in relation to the trays 110 so that the blades during their rotational movement in the direction to feed forward the material alternately spread the material over the tray surfaces and transfer it toward and through the transfer openings 120 from tray to tray.

8. In a mechanical furnace the combination of a furnace casing having a delivery opening to the interior at the top, a feed plate within the casing below the delivery opening, a series of superposed horizontal 130

trays within the casing below the feed plate having transfer openings for passage of material from tray to tray, a central vertical rotatable shaft extending through the trays to the outside of the casing, blades carried upon the shaft so as to overlie the trays, a feed arm rotated with the shaft so as to pass between the delivery opening and the feed plate and to sweep a portion of material from below the delivery opening and off the feed plate on to the first tray, two rollers carried upon opposed sides of the

shaft outside the casing and a fixed cam coaxial with the shaft below the rollers so as, during rotation of the shaft in the direction to feed forward the material, alternately to raise the shaft with the blades in relation to the trays to spread the material and to lower it so that the blades contact with the tray surfaces and transfer the material toward and through the transfer openings.

In testimony whereof I affix my signature.
LEONARD HUGH BONNARD.
